UNITED STATES PATENT OFFICE

2,595,538

DOWNSPOUT STRAINER

Eugene E. Rausch, Marysville, Ohio, assignor of
one-half to William L. Coleman, Marysville,
Ohio

Application August 8, 1950, Serial No. 178,264

3 Claims. (Cl. 210—90)

1

My invention relates to a downspout strainer. It has to do, more particularly, with a strainer or trap for use in a downspout or similar pipe to permit free passage of water but to catch or traps leaves, twigs, et cetera, which tend to clog sewer lines.

One of the objects of my invention is to provide a strainer or trap of the general type indicated which is located in the downspout so that it can be reached from the ground level, thereby eliminating the necessity of removing and cleaning the usual strainers which are located in the gutters and which are usually so high that ladders are required to reach them.

Another object of my invention is to provide a strainer or trap which is easily accessible and which can be removed easily from the downspout for dumping the leaves and trash therefrom.

Another object of my invention is to provide a downspout strainer which is so designed that it will not interfere with the normal water flow through the downspout and will not normally allow leakage of water from the downspout adjacent the strainer.

Still another object of my invention is to provide a downspout strainer or trap of the type indicated which includes a strainer member that can be removed readily when it deteriorates and be replaced with a new one.

Another object of my invention is to provide a downspout strainer or trap arrangement which is simple and inexpensive and can be readily mounted on the usual sheet metal downspout pipe.

Various other objects will be apparent.

The preferred embodiment of my invention is illustrated in the accompanying drawing wherein similar characters of reference designate corresponding parts and wherein:

Figure 1 is a perspective view showing my device mounted on a downspout.

Figure 2 is a vertical sectional view through a downspout showing my strainer in normal operating position therein by full lines and by dotted lines in a position to permit removal and emptying of the strainer.

Figure 3 shows the U-shaped wire which supports the strainer.

Figure 4 is a diagrammatic view illustrating how the strainer can be located in a readily accessible position in the downspout.

With reference to the drawings, I have illustrated my device as comprising a section of sheet metal pipe 10 which is of the same size as the downspout with which my device is to

2

be associated. The section 10 has slidably mounted thereon for axial movement a sleeve 11. The pipe section 10 is provided with an elongated slot or opening 12 which extends one-half of the circumference of the section 10. The axially movable sleeve 11 is of sufficient length to completely close the opening 12 when in one position which is determined by a stop lip 13 formed at one end of the opening 12. It can be slid in the opposite direction to practically completely expose the opening 12.

Connected to the end of the sleeve 11 which is adjacent opening 12 is a U-shape wire or rod 14. This wire, which is shown best in Figure 3, 15 has its outturned ends 15 snapping into diametrically opposed openings 16 in the sleeve 11. These outturned ends 15 will limit sliding movement of sleeve 11 in opening-uncovering direction by contact with the end of opening 12, as 20 shown by dotted lines in Figure 2.

The lower transverse portion 17 of wire 14 is adapted to removably support a strainer 18. This strainer 18 is preferably of wire mesh and is provided with a pair of inverted U-shape clips 25 19 on its bottom which will straddle transverse portion 17 of wire 14. The strainer 18 is preferably of inverted frusto-conical form to facilitate insertion into the pipe section 10. The strainer 18 will be of less axial length than the opening 12 to permit passage therethrough.

As pointed out above and as illustrated in Figure 4, the strainer arrangement may be located in the downspout D in a convenient location readily accessible from the ground level.

35 The position of strainer 18 in normal use is shown by full lines in Figure 2. In this position, the strainer 18 will be located well below opening 12 and sleeve 11 will completely cover the opening, its downward position being determined by the outturned lip 13. In this position, strainer 18 will permit downward passage of water but catch leaves, twigs and other trash. Also, opening 12 will be sealed. When it is desired to remove the trash, the sleeve 11 is moved vertically 40 on section 10. The sleeve is moved to its uppermost position, shown by dotted lines in Figure 2 and determined by portions 15 of wire 14 contacting with the upper end of opening 12. In this position of sleeve 11, relative to opening 12, strainer 18 will have its upper edge below the lower edge of sleeve 11 and its lower edge above the lower edge of opening 12. Thus, the basket strainer 18 can be swung outwardly about pivot 45 17 and can then be slipped axially off the pivot. 50 The trash can then be dumped from the basket 55

strainer and the strainer can be replaced on the pivot 17 or a new basket can be substituted therefor. Then the sleeve 11 is lowered to close opening 12 and return strainer 13 to its normal functioning position. As the strainer moves downwardly it is centered in pipe section 10 due to its inverted frusto-conical shape.

My device has many advantages some of which have been specifically discussed and others of which will be apparent.

Having thus described my invention, what I claim is:

1. A strainer for use in a downspout comprising a pipe section of annular cross-section having an opening therein which extends one-half the circumference of the pipe section, a sleeve of greater length than said opening fitting around the pipe section and mounted for axial movement thereon into and out of covering relationship with said opening, the lower edge of the opening having an outturned lip which limits downward movement of the sleeve, a strainer member of inverted frusto-conical form attached to said sleeve and movable axially therewith so that it will be opposite the opening when said sleeve is moved into opening-uncovering position, said opening being of greater length axially than said strainer member, said strainer member being attached to said sleeve by a U-shape wire which has its upper ends connected to said sleeve, said wire having a transverse lower portion, and inverted U-shape clips on the bottom of said strainer member which straddle said transverse portion.

2. A strainer according to claim 1 wherein said U-shape wire has outturned upper ends which snap into diametrically opposed openings at the lower end of said sleeve.

3. A strainer for use in a downspout comprising a pipe section of annular cross-section having an opening therein which extends at least one-half the circumference of the pipe section, a sleeve of greater length than said opening fitting around the pipe section and mounted for axial movement thereon into and out of covering relationship with said opening, the lower edge of the sleeve and the lower edge of the opening being provided with stop portions which cooperate to limit downward movement of the sleeve, a cup strainer member attached to said sleeve and movable therewith so that it will be opposite the opening when said sleeve is moved into opening-uncovering position, said opening being of greater length axially than said strainer member, said strainer member being attached to said sleeve by a U-shape wire which has its upper ends connected to said sleeve, said wire having a transverse lower portion, and inverted U-shape clips on the bottom of said strainer member which straddle said transverse portion.

ing a pipe section of annular cross-section having an opening therein which extends at least one-half the circumference of the pipe section, a sleeve of greater length than said opening fitting around the pipe section and mounted for axial movement thereon into and out of covering relationship with said opening, the lower edge of the sleeve and the lower edge of the opening being provided with stop portions which cooperate to limit downward movement of the sleeve, a cup strainer member attached to said sleeve and movable therewith so that it will be opposite the opening when said sleeve is moved into opening-uncovering position, said opening being of greater length axially than said strainer member, said strainer member being attached to said sleeve by a U-shape wire which has its upper ends connected to said sleeve, said wire having a transverse lower portion, and inverted U-shape clips on the bottom of said strainer member which straddle said transverse portion.

EUGENE E. RAUSCH.
